UNITED STATES PATENT OFFICE.

MORTIMER ARTHUR CODD, OF LAMBETH, ENGLAND.

IGNITION DEVICE FOR INTERNAL-COMBUSTION ENGINES.

1,297,102.

Specification of Letters Patent. Patented Mar. 11, 1919.

Application filed September 7, 1916. Serial No. 118,864.

To all whom it may concern:

Be it known that I, MORTIMER ARTHUR Codd, a subject of the King of Great Britain, residing at 64 Belvedere road, Lambeth, in 5 the county of Surrey, England, have invented certain new and useful Improvements in or Relating to Ignition Devices for Internal-Combustion Engines, of which the following is a specification.

10 This invention relates to coil ignition devices for internal combustion engines of the kind previously proposed in which the coil, the low tension contact breaker therefor and the distributor, that is, the high tension 15 switch worked by the engine to direct the high tension current from the coil to the sparking plugs, are combined together in a single mechanism the coil being secured to and rotating with a spindle by means of 20 which the distributor and the low tension contact breaker are operated. The chief object of the said invention is to provide a coil ignition device of the said kind which shall be more convenient and economical to 25 manufacture and more reliable, convenient and durable in use than devices of the said kind and form as heretofore proposed.

The chief feature of the said invention is that a single comparatively long bearing is 30 provided for the aforesaid spindle which bearing extends within the casing from one end thereof the main portion of the extension of the bearing being situated within the coil which is secured to the spindle at 35 and near that end of it farther from the end of the casing in which the spindle is situated. The coil therefore overhangs, as it were, the extension of the spindle bearing, which extension is preferably of soft iron 40 and extends for the effective length of the coil thus forming the core thereof. By the construction described a bearing for the spindle on each side of the coil is dispensed with while the device is of minimum bulk 45 and the casing may be readily opened without interfering with the spindle or coil in any way. Other features of the said invention are that the condenser and the low tension contact breaker as well as the rotatory part of the distributor may be arranged to rotate with the coil thereby reducing brush or sliding electrical contacts to a minimum and enabling the condenser and low tension contact breaker to be disposed within the 50 same chamber within which the coil and distributor are situated which arrangement

has not been heretofore proposed in devices of the aforesaid kind although in a form of coil ignition device in which the coil is stationary it has been proposed to inclose 60 the parts in a single casing. The said invention also consists in the general construction and arrangement of parts hereinafter described.

The said invention is hereinafter particularly described with reference to the accompanying drawings which illustrate a convenient embodiment thereof.

Figure 1 of the said drawings is a side view of the apparatus. Fig. 2 is a plan. 70 Fig. 3 is a side view of the upper part of the apparatus looking in a direction the reverse of that from which Fig. 1 is taken. Fig. 4 is a face view of the inner side of the closing cap hereinafter referred to. Figs. 5, 6, 75 and 7 are respectively an edge view, face view of an upper side and face view of the under or cam side of the cam ring and timing lever hereinafter referred to. Fig. 8 is a vertical section of the apparatus taken on 80 the line A A Fig. 2 looking in the direction of the arrows near that line but drawn to a larger scale than that figure. Fig. 9 is a plan view of the apparatus with the aforesaid closing cap and cam ring and timing 85 lever removed. Figs. 10 and 11 are respectively a side view and plan of the spool on which the coil is arranged. Fig. 12 is a perspective view of the distributor contact hereinafter referred to and Fig. 13 is a diagram illustrating the electrical connections. 90

Figs. 9, 10, 11 and 12 are drawn to the same scale as Fig. 8.

In the following description the various parts of the said figures are referred to by 95 the numerals marked thereon the same reference numerals indicating the same parts in the several figures.

1 is the driving spindle for the rotatory parts of the device. 2 is one of the platinum 100 points of the low tension contact maker and breaker carried by a split collar clamped around the spindle 1 as shown in Fig. 9 with interposition of electrical nonconducting material 3. The other platinum point 4 is carried by a spring sheet metal annular plate 5 secured to the collar 6 which is secured to the spindle 1. The low tension contact breaker is therefore carried by and rotates with the spindle 1.

110 The collar 6 forms part of the spool carrying the coil which thus rotates with the

spindle. The spool consists of the said collar 6, and overhanging flange 7 thereon, a tubular portion 8 and a flange 9 at the other end. The whole of the spool is slit from one end to the other and from the most central part to the periphery at 10 (as shown in Figs. 10 and 11) in order to obviate eddy currents. The coil consists of the primary winding diagrammatically indicated at 11 in Fig. 8 and the secondary or high tension winding diagrammatically indicated at 12. Between the upper end of the coil and the collar 6 and within the flange 7 on that collar a condenser is arranged in shunt with the platinum points 2, 4 as usual. The condenser is diagrammatically indicated at 13 in Fig. 8 and it may be formed by annular plates of electrical conducting material and di-electric alternately arranged around the tubular portion 8 of the coil spool within the flange 7 or alternated strips of these materials wound volute fashion around the said tubular portion within the said flange. The working parts of the apparatus are within a tubular casing 14 of ebonite secured in some convenient fixed position and the said casing has secured at its ends metal caps 15, 16. The cap 15 is permanently secured to the casing 14 by screws and constitutes a bearing for the spindle 1 but the cap 16 is removably secured in place by pins 17, 17 on it engaging in holes in blade springs 18, 18 screwed to the cap 15. The normal position of the said blade springs is as illustrated, in which they hold the closing cap 16 in place but by pressing them outwardly from the casing 15 against their resilience the pins 17, 17 are readily disengaged from them to release the cap 16 which can then be easily removed. The upper part of the casing 14 is provided with a small glass window 19 by which the action of the low tension contact maker and breaker may be observed. The cap 16 at the part engaging within the casing is cut away at 16 (see Fig. 4) so as to leave the window 19 unobstructed. Centrally screwed into the cap 15 is a tube 20 of soft iron which projects upwardly between the spindle 1 which it surrounds and the inner surface of the tubular part 8 of the coil spool. This tube 20 constitutes a soft iron core for the coil and also an extension of the bearing in the cap 15 for the spindle 1 by which means the said spindle is provided with one long bearing and a bearing at the low tension contact maker and breaker is avoided thus providing for free access to the parts of the latter device. The cap 16 carries at its center the low tension leading in terminal 21 for the primary winding 11. This terminal is mounted in an ebonite plug 22 screwed into the cap 16 and is provided with a tubular part 23 within which is situated a metal brush plug or contact piece 24 pressed toward the spindle 1 by a coiled spring 25. In a recess in the end of the spindle 1 a leading in plug conductor 26 is embedded in electrical non-conducting material 27 to insulate it from the said spindle and a laterally situated lead 28 from this plug 27 is electrically connected to one end of the primary winding of the coil. The platinum point 2 is connected to the other end of the primary winding by the conductor 29 of thin sheet metal. The platinum points 2, 4 which rotate with the spindle 1 are separated and allowed to make contact the one with the other by means of stationary cams on a cam ring 30. This cam ring is of fiber secured to a metal ring 31 and the rings 30, 31 together are seated in a circular recess in the cap 16. The cams are formed by plane surfaces of the cam ring 30 against which a protuberance 32 on the annular spring plate 35 bear during rotation of the spindle 1 separating the platinum points 2, 4 as shown in Fig. 8. Between the said plane surfaces are equidistantly disposed recesses 33, 33, (see Figs. 5 and 7) which as the spindle 1 rotates admit of the protuberance 32 and plate 35 rising, in consequence of the resilience of the latter, as the said protuberance passes into the said recesses successively thus permitting the platinum points 2, 4 to make contact one with the other from time to time. The electrical current through the primary winding 11 of the coil is thus periodically broken and allowed to flow as necessary. The ring 31 is provided with a radial extension 34 which protrudes through a slot 35 in the cap 16 and constitutes a timing lever, variation of the position of which admits of variation of the time of make and break of the current through the primary coil in relation to the time of passage of current from the secondary winding 12. One end of the secondary winding of the coil is electrically connected to one end of the primary winding and to the condenser 13 and the other end of the secondary winding is connected to a distributor terminal 36 secured to the outside of the coil. Around the casing 14 are equally spaced the terminals within which are respectively secured the several conductors to the sparking plugs of the respective cylinders of the internal combustion engine. In the example illustrated four such terminals are shown. Each has a pointed conducting part 37 the point of which takes up current from the terminal 36 as it passes by the said part 37 during rotation. A proper position for the terminal 36 relatively to the position of the recesses 33, 33 in the cam ring 30 is illustrated in full lines in Fig. 9, but in Fig. 8 the position of the said terminal in passing the part 37 of one of the sparking plug conductor terminals illustrated in that figure is also indicated in 130

broken lines at 38. The coil is surrounded by a sheet of ebonite paper 39 which is held in place by coarse cotton closely wound around it and the exterior of the whole 5 coated with a thin coating of shellac. The terminal 36 is a comparatively thin strip of brass and it is held in place on the exterior of the coil by the following means. The said strip is secured to a thinner but 10 wider and longer strip of brass 40 and an aperture is made in the ebonite paper 39 corresponding to the size of the strip 36 which is placed on the coil so that it protrudes through the said aperture and is held 15 in place by the ebonite paper 39 covering the backing strip 40. This arrangement is illustrated in Fig. 12.

The four terminals for the sparking plug conductors each consist of the conductor 37 20 which is held in place in the casing 14 by the screw nuts 41, 42 and has a split stem 43. On this the parts 44, 45 between which the sparking plug conductor is gripped fit friction tight. These parts are mainly of 25 ebonite but have respectively brass bushings 46, 47 on which the necessary engaging screw threads are formed. The part 45 has an extension formed with a leading in passage 48 for the sparking plug conductor. The construction of these sparking 30 plug conductor terminals forms no part of the said invention.

Fig. 13 well illustrates in diagram the electrical connections and circuits of the apparatus, 49 indicating the battery, 50 a switch and 51 a sparking plug. By examining this diagram and Fig. 8 it will be understood that the circuit through the primary winding 11 is through the terminal 35 21 part 23, brush 24, plug conductor 27, lead 28, through the said winding and conductor 29 to the platinum point 2 thence through the platinum point 4 when it is in contact with the point 2 to the plate 5 which is 40 earthed through the collar 6 and spindle 1. The secondary winding 12 is connected at one end to the primary winding 11 and at 45 the other end to the terminal 36 which conducts current from the conductor 37. The condenser 13 is earthed through the collar 6 and also connected with the primary winding of the coil.

When the spindle 1 is rotated the low tension contact making and breaking points 50 2, 4, the coil and terminal 36 are rotated whereby the platinum point 4 is operated by the stationary cam ring 30 and the terminal 36 brought in succession opposite each 55 conducting part 37 whereby high tension current passes by a jump spark to the sparking plugs of the respective cylinders of the engine in succession as required.

In cases where specially rapid and reliable ignition be desired each cylinder of 60 the engine may be provided with two spark-

ing plugs actuated in series simultaneously. For this purpose the secondary winding 12 is entirely insulated, that is, one end is not connected to the primary winding as in the embodiment hereinbefore described with 70 reference to the accompanying drawings, but the terminal plate 36 is duplicated and one end of the secondary winding is connected to each plate. The terminals for the 75 sparking plug conductors are also duplicated. The two terminal plates are directly above one another on the coil and the two sets of terminals for the sparking plug conductors are also arranged directly above one another on the casing in such 80 positions that when one conductor 37 is passing one plate 36 the conductor 37 of the other terminal for the conductor to the second 85 sparking plug of the same cylinder is passing the other plate 36, one electrode of each plug is connected to earth. The effect of this construction and arrangement is to spark two plugs in series simultaneously.

A coil ignition device made according to the said invention is very compact and while 90 all the parts are inclosed by the surrounding casing ready access to the parts within the said casing may be obtained without materially interfering with any of them or disturbing them in such a way as to render any 95 skilful readjustment or reassemblage necessary.

What I claim and desire to secure by Letters Patent of the United States is:—

1. A coil ignition device of the kind hereinbefore referred to comprising a rotatory spindle, a coil secured to said spindle, and a single bearing for said spindle partly surrounded by said coil. 100

2. A coil ignition device substantially 105 such as hereinbefore described, comprising a rotatory spindle and a coil, a distributor and a condenser, the said coil, the rotatory part of the said distributor, and the said condenser being all carried by the said 110 spindle.

3. A coil ignition device substantially 115 such as hereinbefore described, comprising a rotatory spindle and a coil, a distributor and a low tension contact breaker, the said coil, the rotatory part of the said distributor and the said low tension contact breaker being all carried by the said spindle.

4. A coil ignition device of the kind hereinbefore referred to comprising a rotatory 120 spindle, a coil secured to said spindle, a single bearing for said spindle partly surrounded by the coil, and a condenser secured to said spindle.

5. A coil ignition device of the kind hereinbefore referred to comprising a rotatory 125 spindle, a coil secured to said spindle, a single bearing for said spindle partly surrounded by the coil, and a low tension contact breaker secured to said spindle. 130

6. A coil ignition device substantially such as hereinbefore described, comprising a rotatory spindle, a coil, a condenser, a distributor and a low tension contact breaker, the said coil, the said condenser, the said low tension contact breaker and the rotatory part of the said distributor being all carried by the said spindle.
7. A coil ignition device of the kind hereinbefore referred to comprising a rotatory spindle, a coil secured thereto, a single bearing for said spindle partly surrounded by said coil, a low tension contact breaker secured to said spindle, and a condenser secured to said spindle.
8. A coil ignition device comprising a rotatory spindle and a coil and distributor, the said coil and the rotatory part of the said distributor being both carried by the said spindle, a condenser and a low tension contact breaker, the said coil, distributor, condenser and low tension contact breaker all being within a single casing.
9. A coil ignition device comprising a rotatory spindle and a coil carried by it, a low tension contact breaker, a distributor and a condenser, a single casing inclosing a single chamber in which the said coil, low tension contact breaker, distributor and condenser are located.
10. A coil ignition device of the kind hereinbefore referred to comprising a single casing, a rotatory spindle mounted in a bearing at one end of said casing, one end of said spindle being within but free of said casing, a coil secured to part of the said spindle within the said casing, a low tension contact breaker secured to said spindle near its free end within said casing, a removable portion of said casing adjacent to said free end of said spindle, and means for conducting electric current from outside said casing to the said low tension contact breaker.
11. A coil ignition device of the kind hereinbefore referred to comprising a single casing, a rotatory spindle mounted axially in a bearing at one end of said casing, one end of said spindle being within but free of said casing, a coil and a condenser both secured to said spindle within said casing, a low tension contact breaker secured to said spindle near its free end within said casing, a removable portion of said casing adjacent to said free end of said spindle, means for conducting electric current from without the said casing to said low tension contact breaker, and means carried by said coil for distributing high tension current.

MORTIMER ARTHUR CODD.
